ELECTRICALLY-OPERATED VIBRATORY DEVICES SUCH AS ARE USED IN THE RECORDING OR REPRODUCTION OF SOUND

Application filed December 11, 1928, Serial No. 325,334, and in Great Britain January 30, 1928.

The present invention relates to electrical-
ly operated vibratory devices, such for example, as are used in the recording or reproduction of sounds. The invention is concerned with that type of vibratory device in which the vibratory motion is at least partially rotational about a real or virtual axis and in which the armature length in a direction perpendicular to the axis is at least as great as the distance of the nearer end of the armature from the axis.

It should be noted that in this specification the word armature is intended to cover that part of the vibratory member which lies opposite to and co-operates with a magnet pole surface and the end of the armature nearer the axis of rotation will be referred to as the heel of the armature and the opposite end as the toe thereof.

It has recently been discovered that when an armature of this type is of sufficient length in relation to its radius of rotation, use can be made of the change in the distribution of the magnetic pull between the armature and a magnet pole surface, due to change in shape of the armature which takes place under the influence of the magnetic and other forces. If the vibrator is in the form of a plain cantilever reed, as has commonly been the case hitherto, difficulty has been experienced in providing a sufficiently stiff reed which will not become overstressed even when vibrating at relatively large amplitudes and still obtaining a sufficiently flexible armature. The provision of a relatively stiff portion between a member providing the mechanical restoring force and the armature, however, ensures that the change in shape shall be confined almost entirely to the armature itself.

According to the present invention the vibratory member of a vibratory device comprises an armature of magnetic material and means for mounting the armature for rotation about an axis, that portion of the vibratory member which lies between the axis of rotation and the heel of the armature being stiff in relation to the armature itself.

The invention, in a form suitable for use in connection with the motor element of a

loudspeaker, is illustrated by way of example in the accompanying drawing in which

Figs. 1 and 2 are views in perspective and plan respectively of one form of the invention and

Figs. 3 and 4 are perspective views of alternative forms of the invention.

Referring to Figs. 1 and 2 the vibratory member comprises a cross-bar *b* adapted to be rigidly clamped at its two ends by means of screws *d* to pillars *e* which are rigidly screwed to the base of the instrument, which is not shown. Projecting at right-angles from the cross-bar *b*, and preferably integral therewith, is an armature *a* of rectangular cross-section, and a portion *j* which is stiff, so far as bending is concerned, in relation to the armature *a* is interposed between the cross-bar *b* and the armature *a*. The cross-bar *b* is adapted to twist when the armature vibrates and thus furnish the required restoring force. The armature can be regarded as vibrating about an axis *i* coincident with the centre line of the cross-bar *b*. The stiffening may take the form of webs or, since additional mass close to the axis of vibration is often not of great consequence, the additional stiffness may, as shown, be obtained by simply using a greater thickness of metal.

The vibratory member above described is adapted to be used in an electro-magnetic vibratory device, such as a loudspeaker motor element, in which the armature is mounted for vibration toward and away from a pair of magnet poles *S* (Fig. 4) situated upon one side of the armature. The armature portion of the vibrator extends from the toe to the heel *g* and this portion lies above and co-operates with the magnet poles. The direction of the steady magnet pull is indicated by the arrow *h*. It is usually desirable that the cross-bar *b* should not bend to any great extent and its cross-section is therefore preferably elongated in a vertical direction as shown that is to say in the direction of the magnetic pull. For convenience in manufacture, the under surface of the cross-bar and the under surface (that is the working surface) of the armature are preferably in the same plane as illustrated.

The effect of the stiffened portion in the vibratory member above described in detail is to cause the restoring force due to the torsion of the cross-bar to act, in effect, substantially as if it were applied at the heel of the armature.

A connection rod *m*, or other suitable means, may be provided for connecting the armature with the load (such as a diaphragm) which it is to drive or by which it is to be driven. The point of connection of the load to the armature is preferably disposed between the centre and the heel of the armature and a suitable position for this point has been found to be between one-third and two-fifths of the length of the armature measured from the heel thereof.

It will be clear that equivalent results can be obtained in many cases by pivoting the armature and applying the necessary restoring force in any known or suitable manner.

One such arrangement is illustrated in Fig. 3. The armature *a* is mounted on suitable pivots (not shown) for vibration about the axis *i*, the portion *j* between the heel *g* of the armature and the axis *i* being stiffened as before. A blade *k* projects downwardly from the stiffened portion *j* and bears against a screw *l*. The blade *k* furnishes the restoring force and by rotating the screw *l*, the airgap between the armature *a* and the pole pieces (not shown), which are disposed beneath it, can be adjusted. It will be evident that the blade *k* can project in any convenient direction, for example in the opposite direction to the armature *a*.

In some cases difficulty is experienced in the arrangement of Fig. 3 due to chatter between the blade *k* and the adjusting screw *l*. This difficulty may be overcome by the arrangement shown in Fig. 4 which has also certain other advantages. In this arrangement the two supporting pillars *e* are united by a yoke which is provided with a lug *n*. The vibratory member is of the form described in connection with Figs. 1 and 2 excepting that the stiffened portion *j* is here shown with a straight contour. To the upper end of the portion *j* is attached a thin threaded rod *p* which passes through a hole in the lug *n* and is provided with an adjusting knob *q* threaded thereon. The hole in the lug *n* is arranged somewhat below the level of the top of the member *b* so that the rod *p* is subjected to bending. By screwing up the knob *q* a twisting moment is applied to the member *b* and by this means the air gap between the armature *a* and the magnet poles can be adjusted. Since some stress always remains in the rod *p*, even when the screw *q* is removed, chatter between the rod and the sides of the hole through which it passes is avoided.

In some cases it may be found that in order to obtain a sufficiently flexible armature its thickness has to be reduced more than

may be desirable from other considerations, for example, a certain thickness is required to prevent saturation of the armature. In such cases the armature may be provided with slots, saw cuts or corrugations in a direction substantially parallel with the direction of the magnetic flux in the armature and in the arrangements illustrated the slots would also be parallel to the axis of rotation of the armature. The armature in Figs. 1 and 4 is, for example, provided with grooves *r*. The effect of the grooves or corrugations is to provide increased flexibility of the armature without substantially affecting the cross section of the magnetic flux path through the armature.

I claim:

1. An electromagnetic vibratory device comprising a member mounted for rotary vibration about an axis, an armature connected to said member, a magnet pole and cooperating surfaces on said armature and magnet pole, the length of said surfaces in a direction normal to said axis being at least as great as the distance of the nearer end thereof from said axis, and said member being stiff in relation to said armature.

2. An electromagnetic vibratory device comprising a torsion member clamped at both ends, a member projecting substantially at right angles from and connected to said torsion member, an armature connected to said projecting member, a magnet pole and cooperating surfaces on said armature and magnet pole, the length of said surfaces in a direction normal to said torsion member being at least as great as the distance of the nearer end thereof from the center line of said torsion member and said projecting member being stiff in relation to said armature.

3. An electromagnetic vibratory device comprising a torsion member clamped at both ends, a member projecting substantially at right angles from and connected to said torsion member, an armature connected to said projecting member, a magnet pole and cooperating surfaces on said armature and magnet pole, the length of said surfaces in a direction normal to said torsion member being at least as great as the distance of the nearer end thereof from the center line of said torsion member, said armature being of substantially constant thickness and the average thickness of said projecting member being greater than that of said armature.

4. An armature and a magnet pole adapted to cooperate with said armature and to pass magnetic flux through a flux carrying portion thereof wherein the cross sectional area of said flux carrying portion in successive selected planes parallel to said flux is alternately greater and less.

5. An armature and a magnet pole adapted to cooperate with said armature and to pass magnetic flux through a flux carrying

- portion thereof wherein the side of said flux carrying portion remote from said magnet pole is grooved in a direction parallel to the direction of said magnetic flux.
6. A vibratory member comprising means for mounting said member for vibration about an axis and an armature of magnetic material projecting at right angles from said axis, said armature being grooved in a direction substantially parallel to said axis.
7. A vibratory member comprising an elongated member, an armature, a flexible member connected to said elongated member, said armature and said flexible member projecting from substantially the center of said elongated member in different directions, and connecting means attached to said armature intermediate the ends thereof.
8. A vibratory member comprising an elongated member, an armature, a flexible member connected to said elongated member, said armature and said flexible member projecting substantially perpendicularly from substantially the center of said elongated member in different directions, and connecting means attached to said armature intermediate the ends thereof.
9. A vibratory device comprising a member mounted for rotary vibration about an axis, an armature, a flexible member connected to said rotatably mounted member, said armature and said flexible member projecting in different directions from substantially the center of said elongated member, and connecting means attached to said armature intermediate the ends thereof.
10. A vibratory device comprising a torsion member clamped at both ends, an armature, a flexible member, said armature and said flexible member being connected to said torsion member and projecting in different directions therefrom, and connecting means attached to said armature intermediate the ends thereof.
11. An electromagnetic vibratory device comprising a member mounted for rotary vibration about an axis, an armature connected to said member, a magnet pole adapted to co-operate with said armature and a flexible member connected to said rotatably mounted member and projecting therefrom in a different direction from said armature, the end of said flexible member further from said axis being prevented from vibrating.
12. An electromagnetic vibratory device comprising a member mounted for rotary vibration about an axis, an armature connected to said member, a magnet pole adapted to co-operate with said armature, a flexible member connected to said rotatably mounted member and means for applying variable tension to said flexible member.
13. An electromagnetic vibratory device comprising a member mounted for rotary vibration about an axis, an armature con-
- nected to said member, a magnet pole adapted to co-operate with said armature, a flexible member which is subjected to bending stress connected to said rotatably mounted member and means for applying variable tension to said flexible member.
14. A vibratory member comprising an elongated member, a stiff member projected from substantially the middle of said elongated member, an armature connected to said stiff member, and connecting means attached to said armature intermediate its ends, said armature being substantially more flexible than said stiff member.
- In testimony whereof I have signed my name to this specification.
- MAURICE TROUTON.
